R. GUYOT

TIME STATION INDICATOR

Filed July 25, 1928

FIG. 2.

INVENTOR:

REINHARD GUYOT,

By: *Alta M. Ringer*
his Atty.

UNITED STATES PATENT OFFICE.

REINHARD GUYOT, OF LOS ANGELES, CALIFORNIA.

TIME STATION INDICATOR.

Application filed July 25, 1928. Serial No. 295,281.

This invention relates to devices used by streetcar and railroad men to indicate the proper times at which certain stations are to be reached.

5 One of the objects of this invention is to facilitate a setting of an indicator to show the proper time at which any station is to be reached regardless of the starting time.

Another object is to provide a station-indicating dial adjustable and in relation to the time-indicating dial of a clock.

Another object is to provide a reversible station-indicating dial having on one side the stations in an order in which they follow in one direction, while the same stations appear on the opposite side in the order in which they follow in the opposite direction.

Other objects will appear from the following description and appended claims as well as from the accompanying drawing, in which—

Fig. 1 is a front elevation of a timepiece with a station-indicating dial surrounding the time-indicating dial of the timepiece to indicate the proper time at which any of the stations is to be reached regardless of the starting time according to this invention.

Fig. 2 is a fragmentary cross section through a casing and adjustable dial with means whereby the dial can be clinched to the edges of the casing.

Considering that railroads and especially streetcars traverse the same route repeatedly and often many times a day whereby the conductor or operator is held to certain schedules to reach certain points at a certain time, though traffic or other conditions frequently interfere either with the beginning or during the run of certain trips, it will be clear that printed schedules are not very satisfactory since a conductor or operator is under existing conditions frequently compelled to figure out his own schedule and only comparatively follow the instructions from his main office.

The principal feature of this invention is therefore to give the conductor or operator a chance to equally adjust or reset his indicator whenever a change in the schedule becomes necessary through traffic conditions.

As illustrated, a timepiece, as for instance a watch, is roughly indicated in the center of the illustration in Fig. 1 at 3.

An annular indicating dial 4 surrounds the dial of the timepiece 3. This annular

indicating dial is adjustably mounted in relation to the central time dial 3.

If, for instance, a streetcar is supposed to start at five minutes past three from a certain point, as for instance the end of a certain line, the indicating dial 4 is moved around the time dial so that the starting station indicated at 5 is brought into alignment with the large hand 6 of the timepiece. The indicating dial 4 is maintained in this position in relation to the time dial throughout the run of the streetcar to the opposite end of the line.

All different stations commonly used as stops, or the principal crossings, or junctions that such a streetcar is supposed to pass or traverse are provided on the indicating dial, as, for instance, designated by the numerals 7, 8, 9, 10, 11, 12, 13 and 14.

If then on a certain run such a streetcar is unduly stopped or detained through traffic conditions, or accidents, or other occurrences beyond the control of the conductor or operator of such a streetcar, the indicating dial may be reset at the next junction or station indicated on the indicating dial.

For instance, if the station 10 according to the setting illustrated in Fig. 1 should have been reached at 25 minutes past three, however, this certain streetcar has been detained 10 minutes, the indicating dial 4 can be moved around so that the station 10 aligns with the central time dial at 25 minutes to four. It will then be apparent that all following stations are automatically again correctly placed so that the hand 6 of the timepiece will move around on the dial of the timepiece to indicate the proper time at which such remaining stations should be reached.

The indicating dial is preferably designed with two different indicating faces on the opposite sides so that one trip may be shown on one face of the indicating dial while the return trip of the same streetcar can be shown on the reverse or back side of the indicating dial.

This indicating dial is, furthermore, preferably designed that it may easily be removed to be turned from the front side to the back side and to be moved around the time dial of the central timepiece.

In Fig. 2 a simple structure is illustrated which allows such a moving around the central timepiece and which allows a reversing

from one side to the other of the indicating dial.

The indicating dial 4 is provided with a central opening or aperture indicated at 15 5 through which the dial of the timepiece 3 is visible. The edges of the indicating dial are designed to clinch over the edges 16 of a casing 17. A space is provided between the casing 17 and the indicating dial 4 for the 10 timepiece 3 so that the timepiece may be properly held and aligned centrally below the indicating dial 4.

The clincher rim 18 is provided with oppositely disposed clinching edges 19 and 20. 15 This clincher rim is preferably made of yieldingly and suitably elastic material, such as pasteboard or, more preferably, such as rubber so that the edges 19 and 20 will securely clinch over the edges 16 of the 20 casing 17.

The indicating dial 4 is centrally located between the clinching edges 19 and 20. The rings 21 are merely used to form a more rigid structure so that in case where a return 25 indicating dial 4 is desired and where a comparatively strong and elastic clincher rim 18 is used, the elastic clincher rim does not unnecessarily press on the edges of the indicating dial 4, so as to eventually unduly press 30 this indicating dial out of shape.

The reinforcing rings 21 have a tendency of maintaining the indicating dial 4 in flat and properly annular shape within the strongly elastic clincher rim 18.

From the above it will be clear that no 35 particular schedule is to be written for certain days or certain times of the year. A conductor or operator of a street car can easily set the indicating dial in proper relation to the central time dial according to the 40 instructions of his head office and automatically obtain a proper schedule for the various stations along his route.

The head office of a street car company 45 under these conditions has only to provide a certain number of indicating dials for the different routes, the indicating dials for each route being absolutely alike for the various street cars starting at various times from a 50 certain point of such a route. Having received his starting time for the various runs during the day, a conductor or motorman is easily able to get the various time indications

for the various stations along his run by setting the indicating dial to the different 55 starting times in relation to the timepiece of his time-, station-indicator.

Trips on a certain route, of course, may extend over an hour's time and it must be understood that on the same indicating dial 60 a route can easily be indicated for over an hour by using for the second or third hour different colors. On the other hand, several 65 dials, of course, can be used for the several hours. This is merely a matter of choice on the part of a railroad or transportation company, or the conductor, or operator of a train and therefore is well within the understanding and teaching given in this application.

Having thus described my invention, I 70 claim:

1. A time-, station-indicator comprising a centrally disposed timepiece, a casing in which the timepiece is mounted and which extends with its outer edge beyond the outer 75 contours of the timepiece, and an annular station-indicator having stations indicated on opposite sides and having an engaging rim with resilient engaging edges on opposite sides of the indicator adapted to hold 80 the indicator with its opposite flat sides to the edge of the casing.

2. In a time-, station-indicator, an annular station-indicator made of a flat material with a central aperture around which certain 85 stations are marked on the two opposite flat faces of the indicator, adapted to engage over the outer edge of the indicator and a clincher rim having clincher edges projecting over the two opposite flat faces of the 90 indicator.

3. In a time-, station-indicator, an annular station-indicator made of a flat material with a central aperture around which certain 95 stations are marked on the two opposite flat faces of the indicator, adapted to engage over the outer edge of the indicator and a clincher rim having clincher edges projecting over the two opposite flat faces 100 of the indicator, and reinforcing rings disposed on the opposite flat sides near the outer edges of the indicator for holding the indicator within the clincher rim.

In testimony that I claim the foregoing as my invention I have signed my name.

REINHARD GUYOT.
